[57] ABSTRACT

An assembly for use in cleaning out the pipeline used on ram cylinder type concrete pumps which is adapted to be positioned in the outlets of the pump, upstream of the pipeline valves and hopper valves which regulate the flow of concrete to and from the ram cylinders. The assembly contains a mounting base and a pair of one-way valves, carried by and oppositely aligned in the mounting base, allowing inlet fluid flow to the ram cylinders through one of the valves and outlet flow through the other valve. A hose communicates the inlet valve with a pressurized water supply and a second hose communicates the outlet valve with the concrete pipeline which is to be flushed out.

CLEAN OUT ASSEMBLY FOR A CONCRETE PUMP AND PIPELINE

BACKGROUND OF THE INVENTION

Modern building construction often requires concrete to be pumped to high levels or inaccessible locations where it is poured into forms. The pumps commonly used to move the concrete are of the ram piston type, an example of which is shown in U.S. Pat. No. 3,327,641. Such pumps utilize rams whose ram cylinders are filled with concrete from a hopper during the backstroke, and during the forward stroke, push the concrete into a pipeline which leads to the form. Typically, a pair of rams is utilized, one moving rearward and taking in concrete, while the other moves forward to pump the concrete into the pipeline. Each ram requires a pair of valves for its operation. One is the hopper valve which leads to the hopper. It is open during the rearward stroke of the ram piston associated therewith, during which time concrete is flowing from the hopper into the ram cylinder. The hopper valve then closes during the forward stroke of the ram piston to prevent concrete from being pushed back into the hopper. The other valve associated with the one ram is the pipeline valve which is positioned in front of the ram. The pipeline valve is open during the forward stroke of the ram piston to allow concrete to enter the discharge conduit and is closed during the backstroke to prevent concrete from returning through the pipeline to the ram.

Upon completion of the concrete pouring operation utilizing the concrete pump above described, it is necessary to clean out the pipeline through which the concrete is pumped. It would appear that if water were poured into the hopper, it could be driven by the same ram piston operation through the pipeline, thereby cleaning the cement therefrom. However, the hopper valves and pipeline valves are designed to operate in conjunction with highly abrasive concrete and not water. As a result, they do not generally contain water-tight seals and therefore are not suitable for such a water flushing operation. The pipeline cleaning valve thus involves the inefficient use of existing equipment which is supplemented by the laborious process of manhandling the line for use with an additional pumping system, an economically undesirable solution.

SUMMARY OF THE INVENTION

Briefly, the invention consists of placing a pair of one-way valves, oppositely aligned, in the outlet of a ram cylinder concrete pump, communicating one of the valves through a flexible hose with an external pressurized water supply, such as an outdoor faucet, and the other through a similar hose with the concrete pipeline. The ram pistons of the pump then operate to drive the water fed thereto through the upstream valve, out the downstream valve at high pressures into the pipeline, washing the concrete therefrom.

It is, therefore, the principal object of the invention to provide an assembly for use with a ram piston concrete pump to effectively clean out a concrete pipeline.

IN THE DRAWINGS

FIG. 1 is an elevation of a ram cylinder concrete pump mounted on a truck and connected to a concrete pipeline wherein pivots are provided in the outlet of the pump, dotted lines showing the hopper and valve as-

sembly in the upraised position for mounting of the clean out assemblies.

FIG. 2 is a plan view of a concrete pump showing the hopper valves and outlet pivots.

FIG. 3 is a cross-sectional view taken along line 3-3 in FIG. 2, showing a clean out assembly mounted in one of the outlets and the hopper and valve assembly resting thereon.

FIG. 4 is a cross-sectional view taken along line 4-4 in FIG. 3 showing the one-way valves mounted in the clean out assembly.

FIG. 5 is a cross-sectional view taken along line 5-5 in FIG. 3 showing a frontal view of the one-way valve.

FIG. 6 is a sectional view taken along line 6-6 in FIG. 3 showing the backside of a clean out assembly with hoses communicating with the one-way valves.

FIG. 7 is an elevation of a ram cylinder concrete pump mounted on a trailer with dotted lines showing the hopper and valve assemblies in the pivoted position for mounting of the clean out assemblies.

Referring now in detail to the drawings, FIG. 1 illustrates a hydraulically driven ram piston type concrete pump 10 mounted on a truck 12. The pump moves concrete received in a hopper 14 through a discharge conduit 16, outlet 18 and into a pipeline 20. The pump generally comprises an internal combustion engine 22, a pair of hydraulic actuating cylinders 24 [only one being shown in FIG. 1], communicating with ram cylinders 26, as shown in FIG. 2. Concrete dumped into the hopper 14 passes down through feed lines 28 and 30 and into the ram cylinders 24. The ram pistons [not shown] then push the concrete toward outlet 18. The two ram pistons operate alternately to provide a relatively continuous flow of concrete.

The concrete pump has four valves including two hopper valves 32 and 34 and two pipeline valves 36 and 38. As the ram piston moves to its rearward position in one of the ram cylinders 26, the hopper valve 32 opens to allow concrete to fall into the area in front of the ram defined by discharge conduit 16. During this time, the pipeline valves 36 are closed to prevent a backflow of concrete into the hopper. The concrete may be pumped to large heights such as several stories, and unless the pipeline valve 36 were closed, concrete would rush back through the feed line 28. The concrete in the discharge conduit 16 moves into the ram cylinder 26, and when the cylinder is filled and the ram piston begins its forward stroke, the pipeline valve 36 is opened and the hopper valve 32 is closed. The other operating ram and valves 34 and 38 operate in a similar manner but at 180° out of phase, so that when one ram cylinder is going forward the other is moving rearward. This provides a continuous flow of concrete from outlet 18.

If, upon completion of the concrete pumping operation, water were fed into the ram cylinders through the hopper 14 and feed lines 28 and 30, it would appear that the water, as the concrete, could be driven through discharge conduits 16, outlet 18 and the pipeline 20, thereby washing out the pipeline. However, the hopper valves and pipeline valves are not water tight and therefore must be circumvented to effectively carry out such a flushing operation. To bypass the hopper and pipeline valves, pivot assemblies 40 and 42 are provided between the discharge conduits 16 and ram cylinders 26, whereby the hopper 14, hopper valves 32 and 34 and pipeline valves 36 and 38, all of which are carried by the discharge conduits 16, can be pivoted upwardly as

shown in the dotted line of FIG. 1. Pivot assembly 40, shown in FIG. 3, is comprised of a first annular flange 44 positioned at the downstream end of ram cylinder 26 and a second annular flange 46 on the upstream end of discharge conduit 16. The second annular flange 46 is adapted for abutting relationship with the first flange member 44, and the two flange members are joined at their upper ends by a pivot 48. A locking bar 50 is provided, as seen in FIG. 1, to maintain the assembly in the closed position during the concrete pumping operation. It should be noted that the pivots joining the ram cylinders with the discharge conduits are angled inwardly of the central axis of the ram cylinders and discharge conduits, see FIG. 2. This is a result of the two discharge conduits 16 being angled with respect to and communicating through the pipeline valve 36 and 38 with a single outlet 18, necessitating a single axis about which both pivots are free to rotate, thereby preventing any binding between the adjacent flanges in the pivot assemblies.

To commence the cleaning operation, the pipeline 20 is disconnected from outlet 18 by means of coupling 52, shown in FIG. 1. A hydraulic lifting means 54 is activated to lift the hopper and valves to the upraised position exposing annular flanges 44 on the downstream ends of the ram cylinders 26. A cleanout assembly 56 is then placed against each of the annular flanges 44, as shown for one assembly in FIGS. 3 and 4. For purposes of discussion, further reference will be made only to one of the cleanout assemblies, but it should be understood that another assembly may be similarly disposed at the downstream end of the other ram cylinder. In addition to exposing a direct connection for the cleanout assemblies 56 (to be discussed), tilting the hopper and valve assembly, as described, opens a flow path from the hopper 14 and the discharge assembly 32, 36, 16 and 18 by which gravity will cause all the concrete remaining therein to flow outwardly therefrom upon running water therethrough, no additional labor being necessary. Normally this phase of the cleaning operation is accomplished by manually raking the remaining concrete from the discharge conduits 16 and the horizontal portion of the pipeline valve and by manually employing outlet 18. Furthermore, the tilted position exposes the face of the concrete piston for cleaning prior to attaching the cleanout assembly. Normally, the piston face is difficult to see and reach for proper cleaning.

The cleanout assembly 56 is best shown in FIG. 4 and is seen to comprise a mounting base 58, a pair of one-way valves 60 and 62, locking assemblies 64 and 66 and rear outlet chambers 68 and 70. The mounting base 58 has an annular flange portion 72, which is adapted to abut flange 44 of ram cylinder 26, and a central support section 74 which carries the two valves 60 and 62 which replace the hopper valves 28 and 30 and pipeline valves 36 and 38 for the water cleanout operation. Valves 60 and 62 are one-way valves, each having a valve chamber 76 which extends through the support portion 74 of mounting base 58 and communicates a rear outlet chamber 68 or 70 with the ram cylinder 26. Each valve also contains a valve seat 78, valve ball 80, and restraining pin 82. When the fluid flow through the valve chamber is in the direction of the valve, the ball 80 is forced back against the restraining pin 82 and flows continuously through the valve. If the direction of flow were reversed, the ball would be forced against the

valve seat 78, thereby closing the valve and preventing flow therethrough. In the cleanout assembly 56, the two valves 60 and 62 are oppositely aligned as shown in FIG. 4. Valve 60 is positioned to allow upstream fluid flow into the ram cylinder 26, while valve 62 allows downstream flow therethrough from the ram cylinder. Rearwardly disposed of valves 60 and 62 are the rear chambers 68 and 70. As noted above, these rear chambers communicate with valve chambers 76. In addition, they are carried by the mounting base 58 and extend rearwardly therefrom, as shown in FIGS. 4 and 6. Each of the rear chambers 68 and 70 is adapted for threaded engagement with a hose. Chamber 68 communicates with valve 60 and inlet hose 84, while rear chamber 70 communicates with valve 62 and outlet hose 86. The inlet and outlet hoses are, of course, provided with appropriate fittings 88 for threaded communication with the rear chambers.

In operation, the cleanout assemblies 56 are positioned at the downstream end of the ram cylinders and the locking assemblies 64 and 66 are tightened to secure a water-tight seal between the annular flanges 44 on the end of the ram cylinders 26 and the flange portions 72 of the mounting bases of the cleanout assemblies. The inlet hoses 84 are connected to a pressurized water supply such as a common outdoor faucet [not shown] and the outlet hoses 86 are placed in the disconnected end 91 of pipeline 20. When the inlet hoses 84 are in communication with the pressurized water supply and the concrete pump 10 activated, water is drawn into the ram cylinders 26 through valves 60 and driven at high pressure out the outlet hoses through valves 62 by the ram pistons. Because the pump has two rams which are continually moving in opposite directions, water is continuously being drawn into a ram cylinder through one of the inlet valves 60, while it is being pumped by the other ram through the outlet 62 associated therewith. In this way, the one-way valves 60 and 62 of the two cleanout assemblies 56 function similarly to the hopper and pipeline valves used during the pumping of concrete, thereby providing a continuous flow of water at a high pressure into the pipeline 20. In contrast to the pumping of concrete through the discharge conduit 16 and outlet 18 into the pipeline, the water moves through outlet hoses 86 whereupon it enters the pipeline at a high pressure and washes the concrete therefrom before it can set up within the hose.

Finally, as shown in FIGS. 3 and 4, a support stop 90 is secured to the lower backside of mounting base 56 by bolt means 92. When the pump 10 is being used in conjunction with the cleaning assemblies 56 in a flushing operation, the hopper 14 which was raised by hydraulic means 54 is lowered slightly until the annular flange 46 on the upstream end of the discharge conduit abuts stop 90. This removes the continuous strain of the weight of the hopper and associated valves and conduits from the hydraulic lifting means and utilizes that weight to press against the cleaning assemblies, thereby aiding the locking assemblies in maintaining a water-tight seal between the cleaning assemblies and ram cylinders. It should be also noted that while the concrete pump 10 has been described as being mounted on a truck 12, it can also be mounted on a trailer 94 as shown in FIG. 7. Mounting the concrete pump in this fashion has no effect upon either the construction or operation of the cleanout assembly 56, and so the

above description is equally applicable to a trailer mounting.

Various changes and modifications may be made in carrying out the present invention without departing from the scope and spirit thereof. Insofar as these changes and modifications are within the purview of the appended claims, they are to be considered as part of the invention.

What is claimed is:

1. A valve assembly for use in ram piston type concrete pumps with an inlet hose and an outlet hose for cleaning out a pipeline comprising a mounting base, at least two one-way valves, said valves being carried by said mounting base and oppositely aligned thereon for fluid communication to and from said pump upon said valve assembly being secured thereto, means for communicating one of said valves with said inlet hose and the other of said valves with said outlet hose and means for securing said valve assembly to said pump.

2. The combination of claim 1 wherein said communicating means comprises at least two rear chambers, each of said chambers communicating with one of said valves and having an aperture therein adapted to receive the end of one of said hoses.

3. The combination of claim 1 wherein one of said valves is an inlet valve allowing fluid flow therethrough to said pump and the other an outlet valve allowing flow therethrough from said pump, each of said valves having a valve chamber, an internal valve seat within said chamber, a valve ball adapted to be received in said valve seat and a valve retaining means, whereby fluid flow in one direction urges said ball against said retaining means thereby allowing flow about said ball and through said valve chamber while fluid flow in the opposite direction urges said ball against said valve seat thereby closing said valve and preventing fluid flow therethrough.

4. The combination of claim 1 wherein said securing means are carried by said mounting base.

5. A valve assembly for use in ram piston type concrete pumps with an inlet hose and an outlet hose for cleaning out a pipeline comprising a mounting base, an inlet valve, an outlet valve, each of said valves having a valve chamber, an internal valve seat within said chamber, a valve ball adapted to be received in said valve seat and a valve retaining means, whereby fluid flow in one direction urges said ball against said retaining means thereby allowing flow about said ball and through said valve chamber while fluid flow in the opposite direction urges said ball against said valve seat thereby closing said valve and preventing fluid flow therethrough, said inlet and outlet valves being carried by and oppositely aligned on said mounting base for fluid communication to said pump through said inlet

valve and from said pump through said outlet valve, a rear inlet chamber, said chamber communicating with said inlet valve and having an aperture therein adapted to receive said inlet hose, a rear outlet chamber, said outlet chamber communicating with said outlet valve and having an aperture therein adapted to receive said outlet hose and means for securing said valve assembly to said pump.

6. The combination of claim 5 including a support stop carried by said mounting base, said stop being adapted to abut a portion of said pump upon said valve assembly being secured to said pump so that the weight of said portion of said pump urges said valve assembly against said pump.

7. The combination of claim 6 wherein said securing means is carried by said mounting base.

8. A valve assembly for use with an inlet hose and an outlet hose for cleaning out a pipeline in a ram piston type concrete pump wherein the hopper, outlet conduit which communicates with the ram cylinder and concrete valves carried thereby are pivoted outwardly of the pump, comprising a mounting base having a central support portion and an annular flange portion, said flange portion being adapted to abut the exposed end of said ram cylinder and form a water-tight seal therewith, an inlet valve, an outlet valve, each of said valves being carried by said support portion of said base member and oppositely aligned thereon for fluid communication to said ram cylinder through said inlet valve and from said ram cylinder through said outlet valve, each of said valves having a valve chamber, an integral valve seat within said chamber, a valve ball adapted to be received in said valve seat and a valve retaining means, whereby fluid flow in one direction urges said ball against said retaining means thereby allowing flow about said ball and through said valve chamber while fluid flow in the opposite direction urges said ball against said valve seat thereby closing said valve and preventing fluid flow therethrough, a rear inlet chamber, said chamber communicating with said inlet valve and having an aperture therein adapted to receive said inlet hose, a rear outlet chamber, said outlet chamber communicating with said outlet valve and having an aperture therein adapted to receive said outlet hose and means for securing said valve assembly to said pump.

9. The combination of claim 8 including a support stop carried by said mounting base, said stop being adapted to abut a portion of said pump upon said valve assembly being secured to said pump so that the weight of said portion of said pump urges said valve assembly against said pump.

10. The combination of claim 9 wherein said securing means is carried by said mounting base.
